UNITED STATES PATENT OFFICE.

FREDERICK E. PRÉTAT, OF WATERBURY, CONNECTICUT, ASSIGNOR TO THE
ROGERS & HAMILTON COMPANY, OF SAME PLACE.

DESIGN FOR A SPOON-HANDLE.

SPECIFICATION forming part of Design No. 19,337, dated October 1, 1889.

Application filed August 26, 1889. Serial No. 322,032. Term of patent 7 years.

To all whom it may concern:

Be it known that I, FREDERICK E. PRÉTAT, a citizen of the United States, residing at Waterbury, in the county of New Haven and State of Connecticut, have invented and produced a certain new and original Design for Spoon and Fork Handles, of which the following is a specification, reference being had to the accompanying drawing, forming a part thereof, and which shows a spoon the handle whereof is ornamented in accordance with my design.

The leading features of my design comprise the large foliate spray which occupies the top of the handle and forms the upper boundary of the blank panel, the curved and transversely-extended conventionalized leaf-scroll which forms the lower boundary of the aforesaid panel, and the sinuous leaf-bearing stem developed near the panel and extending downward along the spoon-shank to the upper end of the bowl.

In the drawing, *a* is a blank panel of irregular shape situated near the upper extremity of the handle. The top edge of this panel is defined by a curved foliate spray *b*, which extends from the right-hand edge of the handle

across the top thereof. Just below the stem of the spray just referred to is a small scroll figure *c*, and below the outer end of the spray *30* and at the lower left of the panel a similar scroll *d*.

Extending across the spoon-handle in a curved line, and serving to partially define the lower end of the panel, is a conventionalized leaf-scroll figure *e*. From the same base as the figure *e* is developed a sinuous stem *f*, which proceeds down the handle in curves of diminishing size to the top of the spoon-bowl, said stem bearing near its upper end a large *40* conventionalized leaf-scroll *g*, and both above and below the last-named scroll foliate figures *h*, which are smaller and less prominent.

I claim—

The design for the handles of spoons, forks, *45* and like articles, substantially as herein shown and described.

In testimony whereof I affix my signature in presence of two witnesses.

FREDERICK E. PRÉTAT.
